PULL BOX

Archie Tewart, Jr., West Caldwell, N. J., assignor
to Specialties Development Corporation, Belle-
ville, N. J., a corporation of New Jersey

Application January 27, 1948, Serial No. 4,694

6 Claims. (Cl. 74—502)

1

This invention relates to improvements in pull boxes and the like, and is particularly directed to pull boxes for use in remote control systems which are normally inoperative but which are adapted to be operated upon a predetermined actuation of a control mechanism.

While the present invention is especially concerned with pull boxes for the use indicated, it will be apparent from the description to follow that such pull boxes are also adapted for use in any installation wherein the prevention of unauthorized tampering with the control and an indication that the control has been operated, are desired.

In pull boxes of the character indicated, as at present constructed, the control handle or pull handle is enclosed in a glass covered box or casing, and a hammer or similar device is provided for use in breaking the glass to obtain access to the handle. In such devices, when the glass is broken, particles of the shattered glass are present in the box and often splinters of the glass are retained about the edges of opening, rendering it hazardous to reach into the box for the handle.

Also, in such prior devices, the hammer is often lost, or removed sometimes by mischievous individuals, so that when it becomes necessary to break the glass, a substitute for the hammer must be located, resulting in delay in operating the system.

One of the objects of the present invention resides in the provision of a pull box of the character indicated which is so constructed as to overcome the disadvantages of former pull boxes.

Another object resides in the provision of a pull box which does not require the use of a hammer to break a glass to obtain access to the control or pull handle.

Another object is the provision of a pull box wherein the danger of injury by broken glass is entirely eliminated.

A further object is the provision of a pull box wherein the control or pull handle serves also as the means for rupturing the shield or cover for the box.

A further object resides in the provision of a pull box of the character indicated wherein the portion of the shield or cover for the box remaining after rupturing can readily be removed and a new one substituted.

A still further object resides in the provision of a pull box of sturdy construction; which will withstand the outdoor elements; and which is readily operable.

2

Other and further objects of the present invention will be apparent as the invention is described in greater detail in connection with the accompanying drawing wherein a preferred embodiment of the invention is illustrated.

In the drawing:

Fig. 1 is a front elevational view of a pull box made in accordance with the present invention;

Fig. 2 is a sectional view thereof taken on line 2—2 of Fig. 1; and

Fig. 3 is a view similar to Fig. 2, showing the position of the parts after operation.

Referring to the drawing in detail, 10 designates a pull box constructed in accordance with the present invention comprising a base plate 12 having an aperture 14 formed therein for the reception of a sleeve or socket member 16. The sleeve or socket member has a flange 18 at one end and is screw-threaded on its exterior for the reception of a nut 20. The socket is adapted to be inserted in an aperture in a wall 22, or other support, and when the nut 20 is screwed on the socket member, the flange 18 is brought into engagement with the plate 12, whereby to securely anchor the plate to the wall. Rotation of the plate on the sleeve is prevented by means of a screw 24, which passes through an aperture in the plate 12 and into the wall 22. It is to be understood that if the support 22 be a metal frame, for example, a machine screw or bolt will be substituted for the wood screw illustrated.

A plug 26 is slidably mounted in the sleeve or socket member 16, which plug has a threaded recess 28 formed in its inner end for the reception of an exteriorly threaded cable clamp 30. This clamp has one end of a pull cable 32 clamped thereto, the other end of which is secured to operating means (not shown) for the system to be controlled. The plug 26 has oppositely disposed radial recesses providing a pivotal mounting for the ends of a spring-wire ring constituting an operating or pull handle 34.

The handle 34 serves the dual function of a pull or operating handle for the pull cable, and of means for effecting the opening of the pull box by rupturing the shield or cover for the box, as will be described presently.

The pull box is covered by a frangible shield or cover 36, preferably of transparent plastic material, having a raised cup-shaped central portion surrounded by a flat marginal rim 38. The lower edge of the shield 36 has a substantially arcuate notch formed therein, whereby, in elevation, the shield simulates a modified crescent, with the major portion of its lower or inner edge termi-

nating adjacent the horizontal center line of the pull box, thereby exposing the lower portion of the handle 34, which extends out of the cover through said notch.

The shield 36 is held in place on the base plate 12 by means of a flat ringshaped retaining member 40, which in turn is held in place by screws or bolts 42, whereby the marginal rim 38 of the shield is clamped between the ring 40 and the base plate 12.

If desired, the shield may be provided with a score line or weakened zone 44, as shown in Figures 1 and 2, whereby to facilitate rupturing of the shield along a predetermined line.

When it is desired to operate the system to be controlled, it is merely necessary to grasp and pull the lower end of the handle 34, which projects out of the notch or cut-out portion of the shield, causing the handle to rotate on its pivot and engage the edge of the shield at the cut-out portion and sever the cup-shaped portion from the marginal rim, whereby the handle, together with the plug 26 and the cable clamp 30, can be withdrawn from the box to effect pulling of the cable and the operation of the control mechanism at the remote end of the cable.

It will be noted that the pulling of the handle to effect rupturing of the shield and the pulling of the cable are the result of a single continuous operation, there being no separate operation necessary to first rupture the cover.

Should the cup-shaped portion of the cover not be completely or sufficiently severed by the raising of the handle about its pivot during the initial step of the operation, the completion of the severing or rupturing operation is accomplished when the plug 26 engages the shield upon its withdrawal from the box.

After the system has been operated, the ruptured shield and/or the projecting handle serve as indicating means for indicating that the system has been operated, and that a new shield should be installed. The insertion of a new shield is a simple operation, merely requiring removing the screws 42 and the retaining member 40, removing the marginal rim of the ruptured shield, and inserting a new shield.

When the shield is scored or weakened, as hereinbefore mentioned, the severance of the same will be along the score line 44, which line may be provided in any desired location, whereby the line of severance may be predetermined.

As will be seen from Fig. 1, the opposite portions of the ring-shaped handle 34 engage the opposite arcuate edges of the shield, so as to facilitate the initiation and continuation of the severing operation.

It will be understood that the shield may be semi-circular with either a straight or slightly arcuate lower edge adapted to be engaged by the handle for severance of the shield in the manner described.

It will be seen from the foregoing that the present invention provides a pull box wherein the pull handle for operating a control system serves the dual function of an operating pull handle and of means for opening the box.

It will also be seen from the foregoing that the marginal rim portion of the cover may readily be removed, after severance of the central portion, and a new cover inserted.

While I have illustrated and described a preferred embodiment of my invention, it is to be understood that I do not wish to be limited to that precise embodiment, as obviously various modifications and changes may be made therein with-

out departing from the spirit and scope of my invention.

I claim:

1. In a pull box, the combination of an operating handle; pivotal means for one end of said handle; and a rupturable shield covering the pivoted end of the handle and having an opening through which the other end of the handle extends; said shield having a weakened zone; and said handle being adapted to engage the edge of said shield adjacent said opening, whereby to rupture said shield at said weakened zone when the handle is moved about its pivot.

2. In a pull box, the combination of an operating handle; means providing a pivotal mounting for one end of said handle, the other end of which is free; a rupturable shield having a central cup-shaped portion and a marginal rim, said shield covering the pivoted end of the handle and having an edge terminating intermediate the ends of the handle; and a retaining ring for the shield superimposed on said rim; said handle, when moved about its pivot, being adapted to engage said edge and sever the cup-shaped portion of the shield from its rim.

3. In a pull box, the combination of an operating handle; pivotal means for one end of said handle; a rupturable shield having a central cup-shaped portion, a marginal rim, and a weakened zone intermediate the said portion and rim; said shield covering the pivoted end of the handle and having an edge terminating intermediate the ends of the handle; and retaining means for the shield superimposed on said rim; said handle, when moved about its pivot, being adapted to engage said edge and sever the cup-shaped portion of the shield from its rim at said weakened zone.

4. A pull box for a remote control cable operated system comprising in combination a base plate; a manually operable member; means carried by the base plate providing a pivotal mounting for one end of said member, a frangible shield having an edge terminating intermediate said end of the member and the other end thereof, whereby to cover said first end and to permit access to the said other end; and means superimposed on a portion of said shield for removably clamping the shield to the base plate; said member, when moved about its pivot, being adapted to engage said edge and effect rupturing of a portion of the shield from the clamped portion to permit withdrawal of the handle.

5. A pull box for a remote control cable operated system comprising in combination a base plate; a frangible cover therefor; a plug slidably mounted in an aperture in said base plate and having one end of a cable attached thereto; an operating handle pivotally mounted on said plug and having its free end extending through an opening in said cover; and means for anchoring said cover to said plate; whereby when said handle is moved about its pivot, the pressure of the handle against the edge of the cover adjacent the opening therein will cause a portion of the cover to be severed from its anchored portion to permit the withdrawal of the handle and plug to effect operation of the system.

6. A pull box for a remote control cable operated system comprising in combination a base plate; a frangible cover therefor, said cover having a central cup-shaped portion and a marginal rim; a plug slidably mounted in an aperture in said base plate and having one end of a cable attached thereto; an operating handle pivotally mounted on said plug and having its free end

extending through an opening in said cover; and means for anchoring the marginal rim of said cover to said plate; whereby when said handle is moved about its pivot the cup-shaped portion of the cover will be severed from its rim portion to permit the withdrawal of the handle and plug to effect operation of the system, while the rim portion of the cover is retained in anchored position.
